UNITED STATES PATENT OFFICE.

OLIVER S. RIBLET, OF ERIE, PENNSYLVANIA.

COLLAPSIBLE FORM FOR CONCRETE-WORK.

No. 842,812.

Specification of Letters Patent.

Patented Jan. 29, 1907.

Application filed September 1, 1905. Serial No. 276,758.

To all whom it may concern:

Be it known that I, OLIVER S. RIBLET, a citizen of the United States, residing at Erie, in the county of Erie and State of Pennsylvania, have invented new and useful Improvements in Collapsible Forms for Concrete-Work, of which the following is a specification.

This invention relates to collapsible forms for concrete-work, and consists in certain improvements in the construction thereof, as will be hereinafter fully described, and pointed out in the claims.

The invention more particularly relates to that class of collapsible forms adapted for forming arches, sewers, and the like.

The principal object of the invention is to provide a form which will collapse readily and which may be removed easily from the completed work.

The invention is illustrated in the accompanying drawings, as follows:

Figure 1 shows a section on the line 1 1 in Fig. 2; Fig. 2, a section on the line 2 2 in Figs. 1 and 3; Fig. 3, a section on the line 3 3 in Figs. 1 and 2. Fig. 4 shows a section on the line 4 4 in Fig. 5, Figs. 4 and 5 showing an alternative construction. Fig. 5 is a section on the line 5 5 in Fig. 4. Fig. 6 is a section on the line 6 6 in Fig. 7, Figs. 6 and 7 showing another alternative construction. Fig. 7 is a section on the line 7 7 in Fig. 6.

A marks the roof form. This is made up of any desirable material, preferably wood, and is braced by the webs a. This form may be made in one piece or divided at the top or other places, as desired. Directly under the roof form I place collapsing strips B. These strips extend outwardly beyond the wall of the roof form A. This is a very desirable feature of my invention, in that when the collapsing strip is removed the roof form can be readily dropped downwardly, so as to facilitate its removal. Arranged between

the side strips B are the spreaders C. These are simply blocks of wood having their ends beveled, so that they can be readily removed to permit the collapsing strips B to be drawn inwardly and removed. Immediately under the collapsing strips I provide a collapsing support D. This is preferably in the form of a wedge, as shown in Fig. 1, having the upright part behind which a bar may be placed for withdrawing them. This collapsing support preferably rests on

the bottom form E. The bottom form has the webs similar to webs a.

In forming a sewer, as shown in the drawings, the bottom is ordinarily formed first. The side strips and roof form are then put in place. The spreaders C are then knocked out and the wedges D removed. This loosens the collapsing strips B, so that they may be removed. The collapsing strips B extending beyond the walls of the form A leave a cavity into which the edges of the form A will readily drop, so that it may be readily removed. I prefer also that the collapsing strips B extend outwardly beyond the walls of the form E, so as to facilitate the removal of this form also.

In the alternative construction shown in Figs. 4 and 5 the parts operate in the same way and are similar to those shown in Figs. 1, 2, and 3, heretofore described, except that the collapsible supports are differently formed. In the alternative construction shown in Figs. 4 and 5 the collapsible supports comprise the levers D'. These are pivotally mounted on the collapsible strips B by means of the bolts d. When in place, these supports are vertically arranged, as clearly shown in Fig. 5. Collapsed, the parts are knocked sidewise, thus allowing the collapsing strip B to be removed.

In the alternative construction shown in Figs. 6 and 7 the bottom form E has a platform e² arranged upon it, and in this construction screw-jacks D² form the collapsing supports for the strips B.

While I have shown this invention as adapted to form sewers and have described the top form as the roof form, it is manifest that the collapsible form of the whole or part may be used for making chimneys. As to the broader features of my invention, I do not wish to be limited by the term "roof form" to one that is necessarily on top.

What I claim as new is—

1. In a collapsible form for concrete-work the combination of a roof form and a collapsing strip arranged under the form and extending beyond the walls of the roof form.
2. In a collapsible form for concrete-work the combination of a roof form having the surfaces near the edges of its sides approximating vertical planes and a collapsing strip arranged under one of said edges and extending beyond the walls thereof.
3. In a collapsible form for concrete-work

- the combination of a roof form having the surfaces near the edges of its sides approximating vertical planes; a collapsing strip arranged under the edges of said roof form and extending beyond the walls thereof; and spreaders C between the collapsing strips.
4. In a collapsible form for concrete-work the combination of a roof form and a collapsing strip arranged under the form and extending beyond the walls of the roof form; and collapsible means for supporting said side strip.
5. In a collapsible form for concrete-work, the combination of a roof form and a bottom form, each having its side wall near the edge approximating a vertical plane; and a collapsing strip between said forms and extending outwardly beyond the walls of the roof form.
10. In a collapsible form for concrete-work, the combination of a roof form and a bottom form, each having its side wall near the edge approximating a vertical plane; and a collapsing strip between said forms and extending beyond the walls of the roof form.
15. In a collapsible form for concrete-work, the combination of a roof form and a bottom form, each having its side wall near the edge approximating a vertical plane; and a collapsing strip between said forms and extending outwardly beyond the walls of the roof form.
20. In a collapsible form for concrete-work, the combination of a roof form and a bottom form, each having its side wall near the edge approximating a vertical plane; and a collapsing strip between said forms and extending beyond the walls of both the roof and bottom forms.
25. In a collapsible form for concrete-work, the combination of a roof form; a bottom form; a collapsing strip between said forms; and a collapsible support resting on said bottom form and supporting said collapsing strip.
30. In a collapsible form for concrete-work, the combination of a roof form; a bottom form; a collapsing strip between said forms; and a collapsible support resting on said bottom form and supporting said collapsing strip.
35. In a collapsible form for concrete-work, the combination of a roof form having the surfaces near the edges of its sides approximating vertical planes; a collapsing strip arranged under the edges of said roof form and extending beyond the walls thereof; and spreaders C between the collapsing strips, said collapsing strip supporting said roof form.
9. In a collapsible form for concrete-work, the combination of a roof form; a collapsing strip arranged under and supporting the roof form; and a collapsible support in the form of a wedge supporting the collapsing strip.
10. In a collapsible form for concrete-work, the combination of a roof form having its edges approximating vertical planes; collapsing strips arranged under said spreaders between said collapsing strips; and collapsible supports for said collapsing strips.
11. In a collapsible form for concrete-work, the combination of a roof form having its edges approximating vertical planes; collapsing strips arranged under said spreaders between said collapsing strips; and collapsible supports for said collapsing strips, said strips extending beyond the walls of said form.
12. In a collapsible form for concrete-work, the combination of the roof form A; the bottom form E, said forms having the walls near their side edges approximating vertical planes; collapsing strips B between the edges of said forms extending outwardly beyond the walls thereof; the spreaders C between said collapsing strips; and the wedges D between said collapsing strips and bottom form.
- In testimony whereof I have hereunto set my hand in the presence of two subscribing witnesses.
